GATE VALVE

Clifford E. Anderson, Louis F. Eckert, Jr., and Ronald A. Gulick, Houston, Tex., assignors to ACF Industries, Incorporated, New York, N.Y., a corporation of New Jersey

Filed June 1, 1959, Ser. No. 56,167

Term of patent 14 years

(Cl. D78—1)

Fig. 1

Fig. 2

Fig. 1 is a perspective view of a gate valve showing my new design; and

Fig. 2 is a top plan view thereof on a reduced scale.

The sides of the gate valve not shown are substantially the same in appearance as the sides shown.

We claim:

The ornamental design for a gate valve, substantially as shown and described.
